Wellington A. Sneed INVENTOR.

BY

Curtis Bush ATTORNEY

UNITED STATES PATENT OFFICE

WELLINGTON A. SNEED, OF DAVENPORT, IOWA

SAFETY RAZOR

Application filed March 15, 1930. Serial No. 436,122.

My invention relates to improvements in safety razors.

The objects of my invention are:

To provide a small safety razor or hair cutter which can be used to cut the hair in the nose and ears without danger of cutting the skin or the membranes.

I attain these objects by the means illustrated in the accompanying drawings, in 10 which,—

Figure 1 is a plan view of my device, of approximately normal size;

Figure 2 is an enlarged longitudinal section on the line 2—2 of Figure 1;

15 Figure 3 is a similar section showing the cutting blade omitted;

Figure 4 is an enlarged cross-section on the line 4—4 of Figure 2;

20 Figure 5 is an enlarged detail of one of the cutting blades.

My razor comprises a handle, 1, preferably made from a solid piece of metal with an extended portion, 1a, thereof, milled out into semi-tubular form to form a holder for 25 the blades, 5.

The edges of the extended portion, 1a, are formed with teeth, 2, projecting outwardly therefrom and the teeth, 2, are slightly inclined inwardly.

30 On each side of the holder I mill out a seat, 4, for the blades, 5. The upper corners of the blades, 5, are ground off at an angle, 5a, and lugs or shoulders, 3, are left upon the first and last of the teeth, 2, to form detents for the blades, 5. The shoulders, 3, fit closely against the upper corners, 5a, of the 35 blades and keep them from slipping out of the seats, 4.

In order to assemble this razor conveniently, I provide a fixed retainer, 6, which is a small, semi-circular band of metal, the middle of which is secured to the body, or extended portion, 1a, by a rivet, 6a, or other 45 suitable means.

A removable retainer or holder, 7, formed of a semi-circular bar or plate curved to conform to the curve of the body, 1a, is secured to the body by a bolt, 8, and thumb nut, 8a.

50 The removable retainer, 7, is hollowed out or

curved upwardly at the point where it contacts with the fixed retainer, 6.

I prefer to have the teeth, 2, extend outwardly a little beyond the cutting edge of the blades, 5, so that the blades will not come in direct contact with the skin or mucous membrane, but will cut the hairs without touching the skin. However, as the arrangement of the teeth and the cutting edge of the blade may be varied to some extent to meet 60 individual preference, I do not limit my invention to the particular preferred form shown.

It is obvious that the handle and body may be made from one piece of metal or they may be made separately and suitably secured together and the means for securing the blades against displacement may be varied without departing from the spirit of my invention.

In the operation of my device, the razor is 65 assembled by placing the blades, 5, in the seats, 4, with the lower edges of the central portions of the blades being held between the ends of the fixed retainer, 6 and the adjacent side walls of the body, 1a. The removable retainer is then placed in position, the bolt, 8, inserted and the thumb nut tightened down thereon. I prefer to have the removable retainer, 7, so proportioned that the sides thereof will bear against the blades, 5, and bend the blades slightly in order to secure them 70 securely in place and give the most favorable cutting angle for the edge.

When thus assembled, the cutting end of the razor may be inserted in the nose or ear 75 and the hairs therein cut by a shaving motion without danger of cutting the skin or mucous membranes.

I claim:

1. A safety razor comprising a semi-circular body, a handle united thereto, seats formed in the body on opposite sides thereof adapted to receive small blades, a small semi-circular plate of metal secured to the body adjacent the middle of the seats to form a 85 fixed retainer, a pair of small blades seated in said seats, a removable retainer having a semi-tubular body the edges of which bear against the blades for substantially the full length thereof, seatable within the body, and 90

means for securing the removable retainer to the body.

2. A safety razor comprising a semi-circular body, a handle united thereto, seats formed in the body on opposite sides thereof adapted to receive small blades, a small semi-circular plate secured to the body adjacent the middle of the seats and forming a fixed retainer, a pair of small blades seated in said seats, a removable retainer having a semi-tubular body the edges of which bear against the blades for substantially the full length thereof, and a bolt and thumb nut adapted to secure the removable retainer to the body.

3. A safety razor comprising a semi-circular body with toothed sides the teeth being inclined inwardly on the body, a handle united thereto, seats formed on opposite sides of the body to receive small blades, a fixed retainer formed by a small metal plate secured to the middle of the body adjacent the seats, a pair of small blades fitted to said seats, a removable retainer having a semi-tubular body the edges of which bear against the blades for substantially the full length thereof seatable within the body and means for securing the removable retainer to the body.

4. A safety razor comprising a semi-circular body with toothed sides, a handle united thereto, seats formed on opposite sides of the body to receive small blades, a fixed retainer formed of a small metal plate secured to the middle of the body adjacent the seats, a pair of small blades fitted to said seats, a removable retainer having a semi-tubular body the edges of which bear against the blades for substantially the full length thereof seatable within the body and means for securing the removable retainer to the body, the teeth being inclined on the sides and extending slightly beyond the edges of the blades.

In testimony whereof he affixes his signature.

WELLINGTON A. SNEED.
